UNITED STATES PATENT OFFICE

LOUIS DEL PAPA, OF PAWTUCKET, RHODE ISLAND

ARTICLE HOLDER

Application filed September 21, 1931. Serial No. 564,245.

This invention relates to certain new and useful improvements in article holders.

The primary object of the invention is to provide an article holder in the form of a carton representative of a vehicle having windows on the sides through which are seen the heads and busts of passengers, the vehicle taking the form of a motor bus, an electric car, a railway car, and the like, the articles contained in the holder being themselves moulded in the form of human heads and busts and being viewable through the side window openings of the vehicle, the heads and busts being fastened to sticks or holders to be held in the hand of the consumer. In the present drawing a motor bus is selected as typical of my invention.

A further object of the invention is to provide an article holder of the foregoing character wherein the article comprising edibles, such as candy blocks carried by the sticks are designed to represent the heads of persons and being viewable through the window openings of the vehicle to create the impression of persons riding therein.

With the above and other objects in view that will become apparent as the nature of the invention is better understood, the same consists in the novel form, combination and arrangement of parts hereinafter more fully described, shown in the accompanying drawing and claimed.

In the drawing:

Figure 1 is a side elevational view of a candy holder constructed in accordance with the present invention, showing the heads of the stick candy viewable through openings of the vehicle representation;

Figure 2 is a vertical cross-sectional view taken on line 2—2 of Figure 1, showing the struck-out and folded portions of the vehicle body to provide window openings and supports for the stick candy;

Figure 3 is a horizontal sectional view taken on line 3—3 of Figure 1, showing the upper folds of the window openings; and

Figure 4 is a horizontal sectional view taken on line 4—4 of Figure 1, showing the lower folds of the window openings that

constitute supports for the heads of the stick candy.

Referring more in detail to the accompanying drawing, there is illustrated a candy holder in the form of a box or carton having the representation of a motor bus pictorially represented thereon with the heads of the stick candy viewable through the window openings of the bus, the holder or carton being preferably formed of cardboard or the like that is bent to provide a rear wall 5 and a front wall 6, with a top connecting wall 7, the lower ends of the rear and front walls being spaced from each other as shown in Figure 2. As illustrated in Figure 1, the outer face of the front wall 6 has the representation of a motor bus depicted thereon as indicated by the reference character 7a and said front wall has window openings cut therein as illustrated.

The window openings 8 are separated by spacing strips 9 and are formed by striking out portions of the front wall 6 in rectangular areas resulting in an upper flange 10 directed rearwardly toward the rear wall 5 and a lower flange angularly bent to provide a support 11 and a depending reversely directed brace wall 12. The two flanges struck out from the window opening 8 constitute spacing means for the two walls 5 and 6, while the lower flange of the window opening comprising the walls 11 and 12 constitute a support for the stick candy. The candy is of the character known as a lollipop and includes a stick 13 carrying a candy block 14 upon one end, the candy block 14 being representative of the head of a person or possessing other characteristics, as illustrated in Figure 1. The stick 13 of the candy is inserted through openings in the walls 11 and 12 of the lower flange of the window opening and the candy block 14 rests upon the horizontal wall 11, illustrated in Figure 2, with the candy block viewable through the window openings 8 in the bus representation.

For sanitary purposes, and to maintain the candy in a substantially fresh condition, the holder or carton is covered with a waterproof material 16 of cellophane or similar material that covers the walls of the carton with one

end 16a folded inwardly to overlie the inner face of the rear wall 5 and be positioned rearwardly of the window openings 8 to prevent contact of the candy blocks with the cardboard walls of the carton, while the other end 16b is folded inwardly to overlie the lower edge of the front wall 6.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed, it being understood that the pictorial illustrations of the vehicle may be representative of any other character of conveyance, as an electric or railway car or the like, and that other edibles may be substituted for the stick candy, such as cakes, cookies, buns, and in fact, articles or objects of any character may be displayed through the windows, the primary object of the invention being to provide a carton or holder for objects, wherein the carton or holder may be representative of a vehicle or other structure having window openings therein with articles for display carried by the carton or holder and viewable through the window openings.

I claim:—

1. In a candy holder of the character described, a body having the representation of a vehicle thereon with window openings in the body, candy sticks supported by the body with a candy block on each stick viewable through the window openings, and said candy blocks simulating the heads of persons or objects and representing passengers.

2. In a candy holder of the character described, a body having the representation of a vehicle thereon with window openings in the body, candy sticks supported by the body with a candy block on each stick viewable through the window openings, said body comprising a card board sheet folded to provide front and rear walls with the window opening struck from the front wall, and the material struck from said opening providing a support for the candy sticks.

3. In a candy holder of the character described, a body having the representation of a vehicle thereon with window openings in the body, candy sticks supported by the body with a candy block on each stick viewable through the window openings, said candy blocks simulating the heads of persons or objects and representing passengers, said body comprising a card board sheet folded to provide front and rear walls with the window opening struck from the front wall, and the material struck from said opening providing a support for the candy sticks.

4. In a candy holder of the character de-

scribed, a body having the representation of a vehicle thereon with window openings in the body, candy sticks supported by the body with a candy block on each stick viewable through the window openings, said body comprising a card board sheet folded to provide front and rear walls with the window openings struck from the front wall, and the material struck from said windows providing upper and lower spacing members for the walls with the lower member constituting a support for the candy sticks.

5. In a candy holder of the character described, a body having the representation of a vehicle thereon with window openings in the body, candy sticks supported by the body with a candy block on each stick viewable through the window openings, said candy blocks simulating the heads of persons or objects and representing passengers, said body comprising a card board sheet folded to provide front and rear walls with the window opening struck from the front wall, and the material struck from said windows providing upper and lower spacing members for the walls with the lower member constituting a support for the candy sticks.

6. In a candy holder of the character described, a body having the representation of a motor bus thereon with window openings in the body, candy sticks supported by the body with a candy block on each stick viewable through the window openings, said body comprising a card board sheet folded to provide front and rear walls with the window opening struck from the front wall, and the material struck from said windows providing upper and lower spacing members for the walls with the lower member constituting a support for the candy sticks, and a cellophane covering for the body extending inwardly over the rear wall to space the candy blocks from the cardboard.

7. In a candy holder of the character described, a body having the representation of a motor bus thereon with window openings in the body, candy sticks supported by the body with a candy block on each stick viewable through the window openings, said candy blocks simulating the heads of persons or objects and representing bus passengers, said body comprising a card board sheet folded to provide front and rear walls with the window opening struck from the front wall, and the material struck from said window providing upper and lower spacing members for the walls with the lower member constituting a support for the candy sticks, and a cellophane covering for the body extending inwardly over the rear wall to space the candy blocks from the cardboard.

In testimony whereof I affix my signature.

LOUIS DEL PAPA.
